DESIGN FOR AN OFFSET DOUBLE PROPELLER

Henry Birsh, New York, N. Y.

Application September 1, 1943, Serial No. 111,050

Term of patent 14 years

To all whom it may concern:

Be it known that I, Henry Birsh, a citizen of the United States, residing at New York, in the county of New York and State of New York, have invented a new, original, and ornamental Design for an Offset Double Propeller, of which the following is a specification, reference being had to the accompanying drawing, forming part thereof.

Figure 1 is a perspective view of an offset double propeller showing my new design, and;
Figure 2 is a side elevational view thereof.

I claim:
The ornamental design for an offset double propeller, as shown.

HENRY BIRSH.
